UNITED STATES PATENT OFFICE

2,618,474

FUEL AND AIR MIXING DEVICE

Kenneth C. Agar, Ann Arbor, Mich., assignor to
 Clinton Machine Company, Clinton, Mich., a
 corporation of Michigan

Application July 15, 1950, Serial No. 174,039

5 Claims. (Cl. 261—64)

1

My invention relates to a new and useful improvement in a mixing valve for internal combustion engines and is particularly adapted for use on engines of the one cylinder type. In this class of engines the use of a carburetor is dispensed with and a mixing valve is employed instead.

It is an object of the present invention to provide a mixing valve which will be simple in structure, economical of manufacture, durable, compact and highly efficient in use.

Another object of the invention is the provision of a mixing valve which is adapted for mounting on the tank in which the gasoline or fuel is contained.

Another object of the invention is the provision of a mixing valve of this type of a throttle valve so arranged and constructed that it may be economically manufactured, may be highly efficient in use and may be easily and quickly placed in position or removed therefrom.

Another object of the invention is the provision of a mixing valve embodying a tubular delivery conduit having spirally directed fins or blades on the inner surface thereof for imparting a rotary motion to the fuel mixture passing therethrough for facilitating the mixing of the fuel and the air.

Another object of the invention is the provision of a novel means for securing the air-control valve in position.

Other objects will appear hereinafter.

It is recognized that various modifications and changes may be made in the detail of the structure illustrated without departing from the invention and it is intended that the present disclosure shall be but the preferred embodiment of the invention.

Forming a part of this specification are drawings in which,

Fig. 1 is a side elevational view of the invention showing it applied with parts broken away.

Fig. 2 is a top plan view taken on line 2—2 of Fig. 1.

Fig. 3 is a fragmentary sectional view taken on line 3—3 of Fig. 1.

Fig. 4 is a sectional view taken on line 4—4 of Fig. 1.

Fig. 5 is a sectional view taken on line 5—5 of Fig. 1.

Fig. 6 is an end elevational view of the invention from one end.

Fig. 7 is an end elevational view of the invention from the opposite end.

Fig. 8 is a fragmentary sectional view taken on line 8—8 of Fig. 4.

2

As shown in the drawings the invention is adapted for use with a gasoline or fuel tank 15 having a top 16. The invention embodies a tube 17, formed preferably integral with which is a base 18 which is adapted to be secured by the screws 19 to the outer face of the top 16 of the tank. Formed on the tube 17 and projecting upwardly therefrom is a cup 20 having the outwardly extending flange 22 on which rests a gasket 21 bearing against which is the lower end of the air cleaner 23 which has a cap 24. Projecting upwardly from the base of the cup 20 is a boss 25 which is internally threaded and into which threads one end of a stem 26, the other end projecting thru the cap or cover 24 and being secured in position by the wing nut 27.

Rotatably mounted in the end of the tube 17 is a choke valve 29 which is tubular and which is cut away as at 28 and as at 33. This cut-away portion 28 leaves the end portion intact so that there is a rib 32 at the inner end of slot 28. This valve is provided with a head or flange 30 which bears against the gasket 31 and which is provided with the gripping and indicating portion 30. When the stud 26 is threaded into position the end of the stud will project inwardly of the tube 17 sufficiently to engage in the cut away portion 28 so that the choke-valve is thus held in position in the end of the tube 17. The bottom of the cup 20 is cut away as at 28a so as to register with the cut-away portion 33 so that the air cleaner is thus in communication thru the cut-away portion 33 with the interior of the tube 17.

As shown in Fig. 5 the tube 17 has a cylindrical bore 34 which communicates with the tapered bore 35. The end of the tube 17 is provided with the outwardly projecting flange 36 in which are formed the openings 37 whereby the tube 17 may be connected to the intake manifold of the engine. Formed on the inner face of the bore 35 are spirally directed vanes or blades 38 which are intended to impart a rotary motion to the fuel mixture passing thru the tapered portion 35.

Formed on the tube 17 is the cylinder 39, the tube 17 having the annular flange 40 projecting upwardly therefrom to form a continuation of this cylinder 39. Rotatably mounted in the cylinder 39 is a throttle valve 41 which has at its lower end the circular plate 42 and at its upper end the circular shoulder 43, these parts serving as bearings in the cylinder 39 so that a smooth rotation of the throttle valve 41 may be effected. A cup 44 is mounted on the throttle valve 41 and adapted to overlie the edges of the flange 40, and bear against a gasket 45 so as to prevent the entry of dirt or dust into the cylinder 39. Mount-

ed on the reduced portion 47 of the shoulder 43 is a plate 46, this reduced portion 47 projecting thru the plate 46 and being upset over the same. As shown in Fig. 2 this plate 46 is provided with the outwardly projecting tongue 48 and the nuts 49. Formed in the plate 46 is a hole 50 and projecting downwardly from one side of the plate are the lugs 51 in which is threaded an adjusting screw 52 which is adapted to engage against the post 53 projecting upwardly from the tube 17 and having the angularly turned tongue 54 which is adapted to overlie the plate 46 and prevent upward movement of the throttle valve from its normal position. When the throttle valve is moved so that the nuts 49 register with the tongue 54 the throttle valve may be bodily lifted upwardly out of the cylinder 39. Pivotaly mounted by the screw 56 on the tube 17 is the arm 55, in an angularly turned portion of which is formed an opening 64 in which one end of a spring may be engaged. These springs are not shown as they form no part of the present invention and their use is well known.

An angularly turned tongue 65 is formed on the plate 57 to serve as an abutment for the arm 59 when swung in one direction.

A tube 67 is projected into the tank 15 and is provided at its lower end with a head 68 having a filter screen 69. The upper end of the tube 67 extends into the passage 70 formed in the base 13, this passage communicating with the space 71 between the plugs 72 and 73. Threaded through the plug 72 is a needle valve 74 adapted for controlling the communication of the passage 75 with the space 71. This passage 75 communicates with the passage 76 which is in communication thru the passages 77 and 78 with the interior 34 of the body 17. The flow of fuel through these passages 77 and 78 into the intake manifold through the passage 35 may be controlled by the throttle valve 41 and the amount of flow into the passages 77 and 78 may be controlled by the needle valve 74 embraced by the spring 79. On the end of the member 17, as shown in Fig. 6, there is a flange 80 on which is indicated the direction of rotating the choke valve 29 either to choke position or to running position, a pointer 80 being formed on the end of the valve 29. The operation of the choke valve in an engine with which the invention is used is well known and the rotation of the throttle valve is also well known.

With a construction of this type, there is provided a mixing valve which may be inexpensively manufactured and easily removed and replaced and which is held in position in a novel manner, namely, by the use of the stem 26 and as described.

The throttle valve is also one which may be easily and quickly removed and replaced and which has proven most efficient in use.

What I claim is:

1. In a fuel mixing valve of the class described, a base; a tubular body mounted on said base and open at one end; a cup-shaped body projecting upwardly from said tubular body adjacent one end and having a base, there being an opening formed in the base of said cup-shaped member communicating with the interior of said tubular body; an air cleaner mounted on said cup-shaped body; a threaded stem projected through said air cleaner and threaded through the base of said cup-shaped body to extend into said tubular body for securing said air cleaner on said base; a choke valve inserted in the open end of said tubu-

lar body for closing said end, said choke valve having a cut away portion intermediate its ends for reception of the inwardly projecting end of said stem whereby said choke valve is retained in said tubular body.

2. In a fuel mixing valve of the class described, a base; a tubular body mounted on said base and open at one end; a cup-shaped body projecting upwardly from said tubular body adjacent one end and having a base, there being an opening formed in the base of said cup-shaped member communicating with the interior of said tubular body; an air cleaner mounted on said cup-shaped body; a threaded stem projected through said air cleaner and through the base of said cup-shaped body to extend into said tubular body and to secure said air cleaner on said base; a choke valve inserted in the open end of said tubular body for closing said end, said choke valve having a cut away portion intermediate its ends for reception of the inwardly projecting end of said stem whereby said choke valve is retained in said tubular body; and a cut away portion on said choke valve adapted, upon rotation of said choke valve to one position, for communicating with the opening in said base of said cup-shaped body for controlling the flow of air into said tubular body.

3. In a fuel mixing valve of the class described embodying a base, a tubular body mounted on said base and open at one end, a cup-shaped body projecting upwardly from said tubular body adjacent the open end thereof and having a base, there being an opening formed in the base of said cup-shaped member communicating with the interior of said tubular body and with the interior of an air cleaner positioned on said cup-shaped body; a threaded stem projected through the cleaner and through the base in said cup-shaped body to extend into said tubular body and secure the cleaner on said base; a choke valve inserted in the open end of said tubular body for closing said end, said choke valve having a cut away portion intermediate its ends for the reception of the inwardly projecting end of said stem whereby said choke valve is retained in said tubular body; and a cut away portion on said choke valve adapted, upon rotation of said choke valve to one position, for communicating with the opening in said base of said cup-shaped member for controlling the flow of air through said cleaner into said tubular body.

4. In a fuel mixing valve of the class described embodying a tubular body open at one end and communicating through an opening, adjacent its open end, with an air cleaner mounted on said body at said end and said air cleaner having a threaded stem projected therethrough and threaded into said body for securing said cleaner on said body; a choke valve inserted in the open end of said body for closing said end; an inwardly projecting end on said stem projecting inwardly of said tubular body, said choke valve having a cut away portion intermediate its ends for the reception of said inwardly projecting end of said stem whereby said choke valve is retained in said tubular body.

5. In a fuel mixing valve of the class described embodying a tubular body open at one end and communicating through an opening, adjacent its open end, with an air cleaner mounted on said body at said end and said air cleaner having a threaded stem projected therethrough and threaded into said body for securing said cleaner

on said body; a choke valve inserted in the open end of said body for closing said end; an inwardly projecting end on said stem projecting inwardly of said tubular body, said choke valve having a cut away portion intermediate its ends for the reception of said inwardly projecting end of said stem whereby said choke valve is retained in said tubular body, and a cut away portion on said choke valve adapted, upon rotation of said choke valve to one position, for communicating with said opening for controlling the flow of air through said cleaner into said tubular body.
